(57) **CLAIM**

The ornamental design for a panel for a system chassis, as shown and described.

DESCRIPTION

FIG. 1 is a front isometric view of a panel for a system chassis in accordance with one embodiment.

FIG. 2 is a front elevational view of the panel for a system chassis of FIG. 1.

FIG. 3 is a first side elevational view of the panel for a system chassis of FIG. 1.

FIG. 4 is a second side elevational view of the panel for a system chassis of FIG. 1.

FIG. 5 is a top plan view of the panel for a system chassis of FIG. 1; and,

FIG. 6 is a bottom plan view of the panel for a system chassis of FIG. 1.

The back elevation does not form a part of the design. The broken lines are shown in the figures for illustrative purposes only and form no part of the claimed design.
